SIGNALING SYSTEM.

No. 884,737.

Specification of Letters Patent.

Patented April 14, 1908.

Application filed March 7, 1906. Serial No. 304,610.

To all whom it may concern:

Be it known that I, EDWARD E. KLEINSCHMIDT, a citizen of the United States, and a resident of the borough of Manhattan, city, county, and State of New York, have invented certain new and useful Improvements in Signaling Systems, of which the following is a specification.

My invention relates to signaling systems and has been designed more particularly for single track steam and electric roads where the expense and inflexibility of the systems heretofore in use have made their installation impracticable.

Generally stated the present system comprises a plurality of signals established at suitable points along the road each signal having a designating number. The signal circuits are on the normal danger principle so that from failure of the line or power circuits, breaking of either line or local connections, the signals will instantly move to danger and can not be restored to safety until the disturbing cause has been corrected.

At each signal is a switch which when actuated effects the closing or opening of a shunt circuit around the signal operating solenoid so as to deenergize or energize said solenoid when the signal is to be set at danger and safety respectively. These switches are controlled by an instrument at the home or despatcher's office, said instrument comprising a series of electro magnets two of which are required for the operation of each signal.

In order that the despatcher may be advised of the setting of the signal I provide miniature signals corresponding to and moved in synchronism with the track signals. There is also placed at the despatcher's office an audible or visual signal and a recording instrument which signal and recording instrument are included in the line circuit so as to be operated by the movements of the track signals.

The invention will be understood by reference to the accompanying drawings in which

Figure 1 is a diagrammatic view of the system; Fig. 2 a top view of one of the signal operating switches; Fig. 3 a central section through the controlling instrument at the despatcher's office; Fig. 4 a section on the plane of the line 4-4 of Fig. 2; Fig. 5 a detail of part of the signal operating switch and Fig. 6 a detail view of the make and break

mechanism for operating the audible or visual signal and the recording instrument at the despatcher's office.

Similar reference numerals indicate similar parts in the several views.

Referring to the drawings the numeral 1 designates the main line of a single track road and 2 the sidings, although it is to be understood that the present system is adapted to a double track road and that the reference to a single track road is solely for the purpose of illustration. Any number of signals may be included in the system they being located on a single track road in proximity to the sidings so as to be readily observed by the engineer or motor-man. The signals may be of any standard type mounted in the usual manner and as all of the signals are operated in the same manner it will only be necessary to refer to one of them. In the type shown the semaphore blade 3 is connected by a link 4 to the core 5' of a solenoid 5, the latter being normally energized by current from the power line 80 through a circuit 57, in which is interposed a resistance 58, to hold the blade 3 in safety position. The solenoid 5 is fully deenergized by closing a shunt circuit 56 thus permitting the weighted spectacle end of the blade to move the latter to danger position. When the blade is to be moved from danger to safety a local circuit 59 is closed through a solenoid switch 60 thus throwing the current from the power circuit into solenoid 5 and drawing the core 5' thereof inwardly to lower the blade 3. When the circuit 59 is broken at the switch 60 solenoid 5 will be sufficiently energized by current from circuit 57 passing through resistance 58 to maintain blade 3 in safety position. With this general understanding of the method of operating the signal I will now describe the means by which the movements of any one of the signals along the road are effected.

Located at the despatcher's office is a switchboard 7 having thereon switches corresponding in number to the signals along the road. These switches are alike, two of them being shown in Fig. 1, the first switch having its lever designated 6, and the contact plates 8 and 9. A spring 6² retains the lever in normal position. These switches are adapted to close local circuits through a controlling instrument which as shown in Figs. 1 and 3 comprises a series of electromagnets 110

12, 12', 12'', etc., and a magnet 20 the latter being included in circuit with each of the other individual magnets. The magnets of the controller instrument are mounted in a circle on an insulated base 13, or said base itself may be of insulating material. The armatures 14, 14', 14'', etc., of the magnets 12, 12', 12'', etc., respectively, are pivotally supported on brackets 15 and held in normally retracted position by springs 16. The armature 21 of magnet 20 is also pivotally supported and held in normally retracted position by a spring 22. Supported upon posts 23 secured to base 13 is a ring 24 of insulating material against the under side of which the projecting ends of the armatures 14, 14', 14'', etc., rest when in normal position. To prevent any lateral movement of the armatures their projecting ends may be conveniently guided by pins 24' projecting from the under side of ring 24. Also projecting from the under side of said ring is a stop-pin 21' to limit the upward movement of the outer end of armature 21 in such manner that said end is below the horizontal plane of the projecting ends of armatures 14 and 14'. The magnets are all connected to a common return wire 82.

The plate 8 of the first switch is included in a circuit 10 which circuit also includes the electromagnet 12, and plate 9 is included in circuit 11 which latter also includes electromagnet 12'. The plate 8' of the second switch and magnet 12'' are included in circuit 10', and plate 9' and magnet 12''' are included in circuit 11'. The magnets 12, 12', 12'', etc., control the closing of shunt circuit 56 and magnets 12', 12'', etc., the closing of circuit 59 of the corresponding signal for the purposes above stated. The controller circuits derive current from any suitable source as 81.

It may be here stated that when magnets 20 and 12 are energized the signal of station A will be set at danger, and when magnets 20 and 12' are energized said signal will be set at safety. To set the signal of station B at danger magnets 20 and 12'' must be energized and to set said signal at safety magnets 20 and 12''' must be energized. The magnet 20 is therefore common to all the signals and each signal has two corresponding magnets in the controller circuit. The switches and the magnets of the controller instrument are suitably numbered to correspond with the track signal controlled thereby.

Secured to base 13 is a hollow standard 17 through which passes a spindle 18. The upper projecting end of said spindle carries an arm 19 the normal position of which, as shown in Figs. 1 and 3, is against the projecting end of armature 21 said armature acting as a stop for said arm. To the lower end of spindle 18 is secured a gear-wheel 25 which meshes with a pinion 26 keyed on a shaft 27 (see Figs. 1 and 3). On said shaft 27 is

keyed an ordinary type of alternating current commutator 32. As shown it consists of two complementary sections mortised into each other and separated by insulation 32'. Depending from the under side of base 13 are 70 posts 33 of insulating material to one of which is secured a pair of brushes 34 one of said brushes being always in contact with the upper section of the commutator and the other with the lower section thereof. To the 75 other post 33 is secured a pair of brushes 35, these two brushes lying in the same horizontal plane so that but one is shown in Fig. 3. As commutator 32 is rotated the brushes 35 alternately contact with the upper and lower sections thereof. Commutator 32 and brushes 34 and 35 are included in the line circuit 36 connectpe to a suitable source of energy as 37, the purpose of said commutator being to convert the normally direct current on the 80 line circuit into an alternating current for the purpose of feeding a ratchet wheel 42 included in the signal operating switches as which will be hereafter described.

In its normal position arm 19 on spindle 18 90 is held against the side of the projecting end of armature 21 and at such time the commutator 32 will be at rest. To effect the rotation of commutator 32 when arm 19 is released, I couple shaft 27 with a driving gear 95 31 by means of any convenient clutch. As shown the lower end of shaft 27 has secured to it a cup 28 the inner wall of which is engaged by a friction drag 29 mounted on spring arms 30. The driving gear 31 is 100 keyed to a shaft 31' the upper end of which is stepped into the bottom of cup 28, it being obvious that although gear 31 is continuously rotated no movement will be imparted to shaft 27 while arm 19 is held by armature 105 21, and that the direct current flowing through line circuit 36 will remain normal. When arm 19 is released there is nothing to oppose the force of the friction drag 29 against the inner wall of cup 28 and shaft 27 110 will then be rotated thereby rotating the commutator and converting the direct current on line circuit 36 into an alternating current. At the same time spindle 18 and arm 19 are rotated until the latter is brought to 115 rest by engaging with one of the armatures of the controlling instrument as will be more fully described in the statement of operation of the system. I will now describe the signal operating switch shown in Fig. 2, it being 120 understood that one such switch is located at each signal along the road.

The signal operating switch comprises a polarized magnet 38 which is included in line circuit 36. Projecting between the poles 125 39 of said magnet is a lever 40 pivotally supported at 40'. Lever 40 carries at its outer end a spring pressed pawl 41 which engages the teeth of a ratchet wheel 42. Said ratchet wheel is keyed to a shaft 42' stepped 130

into the arms of a bracket 61 secured to base 84. Adjustably secured to shaft 42' by means of set screws are two projecting fingers 54 and 55 which fingers will be carried 5 around when ratchet 42 is rotated. The fingers 54 and 55 of a given switch are so adjusted on shaft 42' that the lower one 55 is a step in advance of the upper one 54.

Mounted on a bracket 85 secured to base 10 84 is an electromagnet 43 included in line circuit 36. Said circuit being normally closed armature 44 of said magnet is normally attracted. The armature 44 is secured to a stud 44' pivotally stepped in adjustable 15 bearings carried by the arms 85' of bracket 85 and is retracted by a spring 45 when magnet 43 is deenergized. Clamped between collars on the stud 44' and extending longitudinally above and below armature 44 are 20 two spring arms 46 and 47 having transversely projecting heads one of which 51 is shown in Fig. 2. The head 51 of the arm 46 is shown in Fig. 2 and the corresponding head of the arm 47 lies immediately below and is 25 not shown but is similar in all respects. The arms 46 and 47 normally press against a stop-plate 87 secured to the inner side of armature 44 so that they move with said armature when the latter is attracted and 30 retracted and they also have a rearward movement independent of the armature when brought into engagement with the fingers 54 and 55. Secured to the outer side of armature 44 is a block of insulating material 35 88 on which are mounted two pairs of spring contact plates 49 and 50. The plates of each pair are normally separated and the inner one rests against the insulated outer end 53 of the heads 51 and 52. The plates 49 are included 40 in shunt circuit 56, and plates 50 are included in circuit 59.

The operation of the circuit so far described is as follows. It will be assumed that all of the signals are at safety and it is desired to set one of them at danger. For convenience signal A will be known as signal No. 45 1 and signal B as No. 2. When it is desired to set No. 1 at danger the despatcher moves switch-lever 6 into contact with plate 8 thus closing the controller circuits through magnets 20 and 12. When said magnets are 50 thus energized armature 21 will be drawn downwardly so as to release arm 19 and armature 14 will be drawn downwardly so as to lie 55 across the path of said arm when it is rotated. The releasing of arm 19 will permit of the rotation of commutator 32 and spindle 18 and such rotation will continue until arm 19 is brought to rest by engaging armature 60 14. During the rotation of the commutator the current on line circuit 36 will be converted into an alternating current. Owing to the high self-induction of magnet 43 it will be deenergized during the alternations of 65 the current of line circuit 36 and armature 44

with spring arms 46 and 47 will be retracted. In their normal positions with armature 44 attracted the heads 51 and 52 lie across the path of fingers 54 and 55 respectively. When retracted the heads 51 and 52 will be in position to strike against the ends of fingers 54 and 55 respectively. The positioning of these fingers is accomplished by the vibration of lever 40 between poles 39, said lever being alternately attracted and repelled by the alternations of the current on line circuit 36. The fingers 54 and 55 of the switch of signal No. 1 are so adjusted on shaft 42' that when said signal is to be set at danger the vibrations of lever 40 will feed ratchet 42 a sufficient distance to bring finger 54 directly in front of head 51 as indicated in dotted lines Fig. 2. When arm 19 is brought to rest against armature 14 the rotation of commutator 32 will be arrested thus restoring line 85 circuit 36 to normal condition, energizing magnet 43 and attracting armature 44. As the latter moves forward the head 51 of arm 46 will contact with the end of finger 54 thereby keeping said arm backward as armature 44 moves to its attracted position. This results in bringing the two contact plates 49 together thus closing the shunt circuit 56, thereby fully deenergizing solenoid 5 and permitting blade 3 to move to danger. 90 When shunt 56 is opened the current from line 80 passes through resistance 58 the pull of solenoid 5 at such time being insufficient to move the signal and it will remain at danger.

The despatcher retains lever 6 on contact plate 8 until advised by the means later described that No. 1 signal has been set at danger. Lever 6 is then released and rotated until it resumes its normal position shown in 105 Fig. 1. When the controller circuits of magnets 20 and 12 are broken armatures 14 and 21 will resume their normal positions, the former freeing arm 19 which is then rotated until brought to rest against the latter. 110 Through this rotation of shaft 27 and commutator 32 the current on line circuit 36 will be converted into an alternating current thus deenergizing magnet 43 and permitting armature 44 and spring arms 46 and 47 to be retracted. At the same time lever 40 is vibrated so as to restore arms 54 and 55 to normal position. When arm 19 is brought to rest against armature 21 the rotation of commutator 32 will be arrested, magnet 43 will 115 be energized so as to attract armature 44 and arms 46 and 47 will be moved to normal position. When the armature 44 resumes its normal position contact plates 49 will separate thus opening shunt circuit 56.

When signal No. 1 is to be moved from danger to safety the despatcher brings switch lever 6 into contact with the lower plate 9 of the switch-board. This closes the controller circuit 11 through magnets 20 and 12 when 130

the operations above described are repeated except that when arm 19 engages the projecting end of armature 14' the lower arm 55 will be in position to be engaged by the head 52 of 5 the lower spring arm 47. When the rotation of commutator 32 is thus arrested and magnet 43 energized armature 44 will be attracted and in its forward movement will cause the head 52 to strike against the end of finger 55. 10 This results in closing circuit 59 through contact plates 50. Solenoid switch 60 being included in said circuit will be energized thus throwing the current from the power line 80 through solenoid 5. The core 5 of said solenoid being drawn inwardly will restore blade 3 to safety position. When switch lever 6 is 15 moved out of engagement with contact plate 9 arm 19 will be released from engagement with armature 14' and the parts of the controller instrument and of the signal operating switch will be restored to normal positions 20 as already described. When circuit 59 is broken by the separation of contact plates 50 solenoid switch 60 will be deenergized, the interposed resistance 58 in circuit 57 permitting sufficient current to pass to maintain solenoid 5 energized to hold blade 3 at safety. 25

All of the signal operating switches are grouped in series and included in line circuit 30 36 so that whenever arm 19 is released by the movement of any one of the switch-board levers either to the danger or safety contact plates 8 or 9, the magnets 43 of all 35 of the switches will be deenergized and the levers 40 of all of the switches will be caused to vibrate. When the magnet of the controller instrument corresponding to the signal that is to be set arrests the movement of arm 19 then the magnets 43 of all of the 40 switches will be energized and the ratchets 42 of all of the switches will be brought to rest, but the finger 54 or the finger 55 of the switch corresponding to the signal to be set will be the only one in front of the corresponding head 51 or 52. That is when a signal is 45 to be set at danger only one of the fingers 54 of all of the switches will be in front of the corresponding head 51; if the signal is to be set at safety then only one of the fingers 55 of all of the switches will be in front of the corresponding head 52. In order to avoid 50 interference in the setting of the signals it is necessary that the signal operating switches shall be so timed relative to each other that 55 when for example a finger 54 of one of the switches is in position to close the corresponding shunt circuit 56 no other finger 54 of any of the other switches will be in position to close its corresponding shunt circuit 56, and 60 similarly with regard to the fingers 55. This is accomplished by adjusting the fingers 54 of the several switches in such manner that one will be in advance of the other, and the same with regard to the fingers 55. This adjustment is in harmony with the position of 65

the several magnets of the controller instrument. From the above description it will be seen that magnet 12 controls the setting of signal No. 1 at danger and that magnet 12' controls the setting of the same signal at 70 safety. Magnet 12² controls the setting of signal No. 2 at danger and magnet 12³ the setting of the same signal at safety, and so on around the controller instrument there being two controller magnets for each signal. 75 These magnets and the magnet 20 are so disposed in the controller instrument that the projecting ends of their armatures are equidistant so that the same number of alternations of the current on line circuit 36 are obtained when arm 19 passes from one armature to the next succeeding. This will result in positioning either one of the fingers 54 or 55 according to whether the signal is to be set at danger or safety whenever the arm 19 80 after being released by armature 21 is brought to rest by engaging the corresponding armature of the controller magnet. For instance, if signal No. 2 is to be set at danger, arm 19 will not be arrested until it engages with armature 14². During this movement of arm 19 a given number of impulses will be sent over the line 36 to stop ratchet wheel 42 of the switch corresponding to signal No. 2 to 85 properly position its finger 54. If signal No. 90 2 is to be set at safety then the movement of arm 19 will not be arrested until it engages armature 14³. This matter of the proper adjustment of the fingers 54 and 55 for the several switches may be easily effected by means 95 of the set screws. Of course, it will be understood that when signal No. 2 is to be set either at danger or safety position switch lever 6' is moved to either contact plate 8' or contact plate 9'. If signal No. 3 is to be set 100 the despatcher will operate the corresponding lever on the switch-board and so on for all of the other signals along the road, the levers on the switch-board being numbered to correspond with the number of the signal. 105

Embraced within the present system are means for advising the despatcher that the signal has been set according to his intentions and for making a permanent record of the fact. Such means include a series of miniature signals mounted on the switch-board. 110 As shown in Fig. 1 these signals comprise a blade 70 adapted to be moved to danger or safety positions by the movements of cores of solenoids 71 and 72 respectively said solenoids being included in the circuits of the controller magnets of the corresponding track signal. When switch lever 6 of signal No. 1 is moved into contact with plate 8 solenoid 71 will be energized and as the core thereof is drawn inwardly the blade 70 will be moved to danger. When switch lever 6 is moved into engagement with contact plate 9 then solenoid 72 will be energized and blade 70 restored to safety. The movements of 115 120 125 130

the miniature blade 70 advises the despatcher that the controller circuits are in operative condition.

As shown in Fig. 1 the solenoids of the 5 miniature signals are connected to the armatures of corresponding controller magnets so that when arm 19 is arrested by a given controller armature the circuit of the solenoid of the corresponding miniature signal will be 10 closed through arm 19, and as hereafter explained, through contacts 95 and 96.

In order that the despatcher may be advised that solenoid 5 of the corresponding signal has been deenergized and the signal 15 set at danger I secure to the core 5' of said solenoid a notched plate 76. When the blade 3 is at safety the line circuit 36 is closed at the plate 76 by contact therewith of a spring finger 75 resting against it as indicated in 20 Figs. 1 and 6. When solenoid 5 is fully deenergized and the blade 3 moved to danger the plate 76 will be drawn upwardly and as finger 75 rides over the notched surface the line circuit 36 will be alternately opened and closed thus ringing a bell 73 included in said circuit. The notches or serrations on the plate 76 correspond to the number of the signal, that is signal No. 4 will have four serrations, signal 5, five serrations, and so on thus 30 causing the bell 73 to ring the number of the signal that has been set. Also included in the line circuit 36 is any ordinary type of recorder 74 which when operated by the movement of the core 5' of the corresponding signal 35 will make a permanent record on the tape 90 of the number of the signal operated. The bell 73 and the recorder 74 are operated both when the signal is set at danger and safety. By these means the despatcher is fully advised that the proper signal has been set and 40 in case of dispute the record made by the recording instrument 74 will determine the fact.

In Figs. 2 and 4 I have shown means to synchronize the ratchet wheels 42. Secured to the inner side of armature 44 is a bracket 45 65 on the outer end of which is pivotally mounted an arm 64. In an opening in the end of said arm is loosely mounted a follower 63 said follower being held in said opening by 50 a spring 63'. The follower 63 is adapted to engage a spiral groove 62 on shaft 42'. During the normal operation of the system when magnet 43 is energized the arm 64 is moved backward so as to release follower 63 from the cam groove. During the alternations of 55 the current on line circuit 36 when magnet 43 is deenergized the follower 63 moves into engagement with the cam groove and when ratchet 42 is fed the arm 64 will be carried 60 downward and released only when magnet 43 is again energized. Under normal conditions arm 64 is never moved to its lowermost position, said arm being restored to its uppermost position when magnet 43 is energized 65 by the action of a spring 66. In order to in-

sure that the arms 54 and 55 are in proper adjustment I provide a switch 68 in the circuit of magnet 20. When switch 68 is closed magnet 20 of the controller will be energized thus releasing arm 19 and permitting it to rotate as long as switch 68 is closed. This, as above explained, results in deenergizing magnet 43 and permitting follower 63 to remain in engagement with cam groove 62, and ratchet 42 to be fed until arm 64 is carried to its lowermost position. When that occurs a stop-pin 67 on the face of ratchet 42 will contact with a toe 69 on arm 64 thereby arresting the movement of ratchet 42. Stop-pin 67 is so placed that when this contact 75 takes place the arms 54 and 55 will be in normal position. It will be understood, of course, that stop-pin 67 is differently positioned in the several signal operating switches.

As before stated the signal circuits are on 80 the normal danger principle. As shown in Fig. 1 I interpose in the line circuit 36 at each signal a solenoid 91 which being normally energized its core 92 will be drawn inwardly. During the alternations of the current on the 85 line circuit solenoid 91 will not be deenergized sufficiently to allow its core to move outwardly. Should the line circuit be broken solenoid 91 will be deenergized thus permitting core 92 to move outwardly and in 90 so doing to separate the contacts 93 thus deenergizing solenoid 5 and permitting the signal to move to danger. When the break in the line circuit is repaired then solenoid 91 will be energized closing the circuit at contacts 93, the spring 93' being sufficient for 95 that purpose. For the purpose of setting the miniature signals on the switch-board through line circuit 36 I interpose in said circuit, preferably at the despatcher's office, a relay 94 100 the armature 95 of which is normally attracted. When line circuit 36 is alternately opened and closed by the movement of the serrated plate 76 attached to the core of solenoid 75, then relay 94 will be deenergized 105 permitting its armature 95 to engage a contact 96 included in the return circuit of solenoids 71 and 72 of the miniature signals. According to this method when the despatcher moves switch-board lever 6 into engagement 110 with contact plate 8 then solenoid 71 will not be energized. By retaining lever 6 on contact plate 8 and breaking the line circuit 36 by the movement of serrated plate 76 such movement will close the return circuit of 115 solenoid 71 through arm 19 as heretofore explained thus energizing the latter and moving the corresponding miniature signal to danger. In like manner said signal will be moved to safety when solenoid 72 is energized. 120

To enable an operator along the road to set a signal at danger I provide a normally closed switch 97. By manually moving the lever of this switch circuit 57 will be opened thus deenergizing solenoid 5 and permitting 130

the signal to move to danger. The signal may be restored to safety by closing switch 97 and by the despatcher at the switch-board moving the corresponding switch lever 6 into engagement with contact plate 9, the despatcher being notified of the setting of a given signal through the opening of the corresponding switch 97 by the movement of the miniature signal and the operation of the 10 indicating bell 73 and recorder 74.

A feature of importance in connection with the present system is that the line circuit requires but one wire to operate any 15 number of signals. This materially lessens the cost of installation and maintenance and simplifies the entire system in that it does away with relays and special contacts.

What I claim and desire to secure by Letters Patent is:

- 20 1. In a selective signaling system, a plurality of signal stations, signal devices adapted when released to move automatically to stop position, a wire connecting said stations and normally carrying current, electromagnets at the several stations connected to said wire and normally holding the signal devices at clear position, and electrically actuated step-by-step devices adapted to release said signals selectively.
- 25 2. In a selective signaling system, a sending station, a plurality of receiving stations, signal devices at the receiving stations adapted to move to stop position when released, a wire connecting said stations, means at the sending station for normally maintaining a voltage on said wire, electromagnets at the receiving stations connected to said wire and normally holding said signal devices in clear position, and means whereby said 30 devices may be selectively released from the sending station.

3. In a system of the character described, a switch-board, a controller having a series of 45 adjustable stops, a plurality of track signals, switches for operating said signals, and means for setting any one of said stops from the switch-board to operate the corresponding signal switch.

4. In a system of the character described, 50 a track signal, a normally energized solenoid, for maintaining said signal in safety position, a shunt for said solenoid, a normally closed line circuit, a switch for closing said shunt included in said line circuit, and a controller 55 for sending alternating impulses over the line circuit for operating said switch to close the shunt when the signal is to be set at danger.

5. In a system of the character described, 60 a controller comprising a commutator and means to rotate the same, a plurality of magnets and stops controlled thereby, means for energizing a given controller magnet to set its stop so as to arrest the commutator, means for releasing the commutator and for 65 rotating the same when released and until

brought to rest by one of the stops, a line circuit including said commutator, track signals, and means governed by the alternating current impressed on the line circuit to set said signals according to the arrangement of 70 the stops.

6. In a system of the character described, a controller comprising a plurality of electromagnets, a normally closed line circuit, a commutator included in said circuit said 75 commutator being normally at rest, a plurality of track signals, means for energizing said controller magnets to permit the rotation of said commutator, and means governed by the alternating current impressed upon said line 80 circuit when the commutator is rotated to set the signal corresponding to the energized magnet.

7. In a system of the character described, 85 a controller comprising a plurality of electromagnets, an arm and means to rotate the same, said arm being held in normal position by the armature of one of said magnets, a commutator, adapted to be rotated when said arm is released, a line circuit including said 90 commutator, and means controlled by the alternating current impressed on said circuit when the commutator is rotated to set a given signal.

8. In a system of the character described, 95 a controller comprising a plurality of electromagnets having movable armatures, a normally closed line circuit, a commutator included in said circuit said commutator being held at rest by any one of the magnet armatures, controller circuits and means governing the same so as to move the corresponding magnet armature to permit of the rotation of 100 said commutator, track signals corresponding to the controller magnets, and means governed by the alternating current impressed upon said line circuit when the commutator is rotated to set the corresponding signal.

9. In a system of the character described, 110 a controller comprising a plurality of electromagnets having movable armatures, a commutator and means to rotate the same, an arm geared to said commutator so that the latter will be brought to rest by said arm engaging any one on the magnet armatures, track signals corresponding to the controller magnets, controller circuits and means governing the same to release said arm from its normal position and to permit its rotation and the rotation of the commutator until the latter is brought to rest by said arm engaging the armature of the magnet corresponding to the signal to be set, and means governed by the alternating current to set said signal.

10. In a system of the character described, 115 a plurality of track signals, an operating switch for each signal, two circuits adapted to be closed and opened by said switch one of said circuits setting the corresponding signal

- at danger and the other setting it at safety, said circuits being normally open, circuit closers comprising movable arms, fingers projecting into the paths of said arms, and means to position said fingers for the purpose described.
11. In a system of the character described, a track signal, two circuits directly controlling the setting of said signal, a switch comprising rotatably mounted fingers, and means to position said fingers to close the corresponding circuit to set the signal at danger or safety.
12. In a system of the character described, a track signal, two circuits directly controlling the setting of said signal, a switch comprising a ratchet wheel, two fingers carried by said wheel, circuit closers adapted to be moved by said fingers, and means to feed said wheel a pre-determined distance to position said fingers to act upon the circuit closers.
13. In a system of the character described, a plurality of track signals, an operating switch for each signal, two circuits adapted to be closed and opened by said switch one of said circuits setting the corresponding signal at danger and the other setting it at safety, said circuits being normally open, circuit closers comprising two arms, an electromagnet having a pivoted armature on which said arms are carried, said arms being moved by and also having a movement independent of that of the armature, and means for imparting to said arms such independent movement to effect the closing of the corresponding circuit.
14. In a system of the character described, a plurality of track signals a single line wire for controlling the movements of said signals, a series of indicators corresponding to the track signals, and means for operating said indicators by the movements of the track signals.
15. In a system of the character described, a plurality of track signals, a single line wire for controlling the movements of said signals, a series of miniature signals corresponding to the track signals, and means for setting said miniature signals by the movements of the track signals.
16. In a selective signaling system, a plurality of signal stations, signal devices adapted when released to move automatically to stop position, a wire connecting said stations and normally carrying current, solenoids at the several stations connected to said wire, cores for said solenoids connected to said signal devices and normally holding them at clear position, and electrically actuated step-by-step devices adapted to deenergize said solenoids to thereby release said signals selectively.
17. In a selective signaling system, a plurality of signal stations, selective signal-controlling devices at the several stations, electro-responsive means for moving said devices step-by-step, a wire connecting said stations and normally carrying current, and means for actuating all the signals upon a failure of current in said wire.
- In testimony whereof I have hereunto signed my name in the presence of two subscribing witnesses.
- EDWARD E. KLEINSCHMIDT.
- Witnesses:
- OLIN A. FOSTER,
M. E. McNINCH.
